METHOD OF MAKING NON-RIGID ROTATIVE ABRASIVE STRUCTURES

Vincent Meyer, South St. Paul, and Howard F. Payer, St. Paul, Minn., assignors to Minnesota Mining and Manufacturing Company, St. Paul, Minn., a corporation of Delaware

Filed Jan. 24, 1958, Ser. No. 710,838

6 Claims. (Cl. 51—293)

The present invention relates to new and improved methods of manufacturing non-rigid rotative abrasive structures of the nature of those described and claimed in copending Miller and Gothier application Serial No. 545,390, filed November 7, 1955, now abandoned. More particularly the present invention is concerned with novel and advantageous methods of forming abrasive flap wheel structures, which structures are comprised of an annulus of many juxtaposed radially extending flap sections of abrasive sheet material, wherein adjacent flap sections are rigidified and firmly rigidly adhesively bonded together over a substantial radially inner end area to form a rigid reinforced inner rim portion in said structures all across the width thereof.

Abrasive flap wheels of the nature of those described in Miller and Gothier application Serial No. 545,390 can be manufactured by arranging many identically shaped flap sections of abrasive sheet material in superposed face-to-back relation so as to form a block or pack of said flap sections. The flap sections can have a pair of opposed notches in the lateral edges adjacent the ends thereof which are bound together, these notches aligning in the block of flaps to define opposed lateral grooves therein.

In the method specifically described in said Miller and Gothier application Serial No. 545,390, the block of notched flaps is bound together for manipulation into the annulus by applying one or more narrow flexible adhesive coated strips lengthwise along the surface of the block defined by the ends of the flap sections which will form the inner periphery of the annulus, the surface to which the said tape is applied being first primed with the aid of a primer adhesive. The said strips cover only a portion width-wise of the block surface to which they adhere. Liquid curable adhesive is then applied to the remaining exposed area of the taped surface thereby to coat the individual flap sections adjacent the taped block surface. The block is then manipulated into an annulus. Then forming rings are inserted in place in the lateral grooves defined by the aligned notches, following which the tape strips are removed. Additional liquid curable adhesive is applied after removal of the tape strips, inter alia, by painting the inner periphery of the annulus several times with said adhesive. Although this method is operable in all respects to provide the desired abrasive flap wheel structure, it involves numerous procedural steps and tends to be somewhat cumbersome and disadvantageous from the aspects of commercial manufacture. Further, the presence of the primer adhesive and any residuum of adhesive from the tape strips tends to inhibit the uniform incorporation of liquid curable adhesive into the annulus from the inner peripheral surface.

It is an object of the present invention to provide a novel method involving a minimum number of procedural steps and suitable for the efficient commercial manufacture of abrasive flap wheel structures. A further object is to provide a novel method of making abrasive flap wheel structures wherein an assembled block of superposed flaps is simply and easily bound together by stretchable removable binding means, whereby the block easily and quickly can be manipulated into an annulus. A further specific object is to provide a method by which a

block of superposed abrasive flap sections can be manipulated into an annulus without necessity of prior application of adhesive resin, or adhered tape strips. An additional specific object is to provide a commercially practical mode of manufacturing abrasive flap wheels wherein uniform distribution of liquid curable binder adhesive in a flap wheel annulus is attained in a single application step.

The manner in which these and other objects and advantages are achieved will be apparent from the following detailed description of our invention, and from the appended drawing wherein like reference characters refer to corresponding parts in the several views, and in which:

FIGURE 1 is a plan view of an abrasive sheet flap section;

FIGURE 2 is a view in perspective of a block of superimposed flap sections;

FIGURE 3 is a view in perspective showing, at an intermediate stage of the step, the manipulation of the block of flaps into annular form;

FIGURE 4 is a vertical section view of the annulus of flap sections with annular side flanges in place, this view also being at an intermediate stage of manufacture; and

FIGURE 5 is a view, somewhat schematic in character, showing the structure of FIGURE 4 mounted for rotation during subsequent manufacturing procedures.

Flap sections 10 of sheet material, for example including flexible coated abrasive sheet material, are die-cut or otherwise formed to identical generally rectangular shape, each flap section having a single pair of opposed notches 11 and 11a in the lateral edges of the flap sections adjacent one end thereof. The flap sections may take generally the shape of those described and shown in the drawing of said Miller and Gothier application Serial No. 545,390 except that the flaps contain only a single notch in each lateral edge (although, of course, if desired two or more notches can be utilized in each lateral edge). The said flap sections are then assembled in superposed face-to-back relation into a block or pack 12, with the notches in the flap sections aligning in the block to define opposed grooves 13 and 13a in the lateral surfaces thereof. The block 12 of flap sections is then pressed in the longitudinal direction to provide a dense distribution of flaps, a typical pressure being about 35 pounds per square inch. The block or pack of flaps is so compressed that the portion thereof containing the lateral grooves is exposed and accessible, for example the flaps can be assembled and compressed in an elongate channel member having a U-shaped cross section with the ends of the flaps containing the notches extending upwardly and out of the channel.

An elastic member 14 of continuous length, e.g., a conventional so-called "rubber binder," of suitable length is stretched over and about the periphery of the block, generally in a plane perpendicular to the flap sections. The elastic member is then released so as to nestle tautly in place along and within each of the lateral grooves 13 and 13a and about the exposed surface of the flap section at each end of the block 12. Thereby the block is unified temporarily. Then, with the ends of the flap sections adjacent the said notches forming the inner periphery, the block of flaps is manipulated into an annulus with the flap section at each end of the block being brought into face-to-back abutting relationship. This manipulation may involve somewhat of a dexterous trick; but it will be observed, in connection with FIGURE 3, that if the ends of the block are grasped with the hands, without immediate concern for the mid-portion of the block, and if said ends then are quickly brought around toward one another in a generally circular arc the annulus is formed without mishap. The forming operation is conveniently conducted

with the block of flaps lying on its side on a flat supporting surface.

An annular side flange 15 having a center hole of lesser diameter than the inner diameter of the flap wheel annulus just formed, and further having a laterally extending ring 16 adjacent the outer periphery thereof of such size as to coincide with the now circular lateral groove 13 in the flap wheel annulus, is then driven lightly into position with said lateral ring partially extending into said circular groove. The elastic member is cut free from the groove at the opposite surface of the flap wheel. With care being taken not to disrupt the packed annular relationship of the flaps, the elastic member is pulled free of the annulus. Since the side flange was only driven lightly into place, the binder will pull free of the groove into which the side flange was inserted. A second flange 15a, like the first, is then firmly driven into position in the lateral surface of the wheel opposite that retaining the first flange, with the laterally extending ring 16a extending within now circular lateral groove 13a. Following this it may be advisable to invert the wheel and again drive the first applied flange so that the lateral ring of the latter will set more deeply into the groove now free of the elastic member. The flanges serve to retain the radially extending flap sections firmly in uniform densely packed relation at the inner peripheral portion of the annulus pending incorporation of the resinous adhesive material between the flaps.

As schematically shown in FIGURE 5, the flap annulus is then mounted for rotation on a horizontal axis, the speed of rotation preferably being controlled through a motor 17 containing a variable speed drive mechanism 18. Mounting is such that the center hole of one of the side flanges is accessible for the flowing or pouring of adhesive into the central portion of the flap wheel. For example, the flap wheel annulus can be clamped from one side in a horizontally rotatable jaw mechanism which grips the peripheral portions of the flap wheel side flanges thereby retaining the flap wheel on a horizontal axis while leaving the center portion of one flange accessible.

The annulus is rotated, and during such rotation the liquid curable adhesive resin is added, for example through a pour tube 19, through the center hole of the annular side flange into the space in the center of the flap wheel defined therebetween. The liquid resin thus flows onto the inner periphery of the abrasive annulus temporarily forming a pool at the lower portion of the cavity defined by the inner peripheral portion of the annulus and the side flanges. Rotation is at a speed sufficient for centrifugal forces to cause the liquid resin to flow or seep radially outwardly between the wheel flaps. In this fashion the flow of the liquid resin radially outwardly will be uniform all about the inner circumference. Rotation at the initial rate is continued at least until most or all of the resin pool has disappeared. The speed and the duration of rotation should be so limited that the resin is retained at the inner peripheral portion of the abrasive annulus rather than being thrown to the outer portion of the annulus. Preferably the speed of rotation is then reduced to a rate at which the resin no longer is forced radially outwardly between the flaps, rotation at this slower speed continuing until the adhesive resin has cured to at least a non-flowable state.

Heat may be advantageously applied to facilitate the cure-time of the resin and to improve physical characteristics of the thus cured adhesive. This heat source may be employed in the form of a cartridge heater of suitable diameter, the heater being inserted through the center hole between flanges into the cavity.

Following the cure of the resin adhesive the wheel structure is demounted and the side flanges removed, at which time the resulting structure is ready for mounting on a hub or shaft (e.g., with the aid of side flanges) to be used in abrading operations. If desired, the side flanges employed in the manufacture may be of such configuration and design as to be mountable with the flap wheel on a drive shaft. In this instance the flanges need not be re-

moved at the end of the manufacturing procedures, the wheel instead being used or sold with the flanges remaining attached.

In order to facilitate the practice of the method just described, and to assist in the proper determination of rotational speeds, time of rotation, etc., the following specific illustration will be helpful: An abrasive annulus composed of 160 generally rectangular flaps of a size of about $2\frac{1}{2}$ inches by 2 inches was formed by incorporating a 10 conventional rubber binder around and about a block formed of said flaps all in the manner above described. The flaps were composed of grit 50 abrasive mineral adherently coated on a treated drills cloth backing ("Resinbond Three-M-Ite" cloth available from Minnesota Mining and Manufacturing Company, St. Paul, Minnesota). When manipulated into an annulus the flap wheel structure had an outer diameter of 6 inches, an inner diameter of $1\frac{3}{4}$ inches and a width of 2 inches. The annulus was rotatably mounted and then rotated at a speed of about 15 140 r.p.m. One and one-half ounces of curable liquid 20 epoxide-type resin adhesive, like that described in connection with the previous example (diethylene triamine accelerated Bakelite BR-18774), were added to the inner periphery of the flap wheel through the center hole in one 25 side flange. Following the addition of the resin a three-fourth inch diameter 700° F. cartridge heater was inserted into the cavity between the side flanges. Rotation at the initial rate was continued for about a minute and a half following completion of the addition of the resin adhesive. 30 Rotational speed was then decreased to about 24 r.p.m., and rotation at this slower speed was continued for approximately $3\frac{1}{2}$ additional minutes. By this time the adhesive resin had cured to a rigidified state thereby to provide a rigidly reinforced inner rim in the annulus. 35 Following this the structure was demounted from the rotating mechanism and allowed to cool.

The rotational speed, time of rotation, etc. employed in the case of the specific wheel just described may or may not be the optimum values for the manufacture of flap 40 wheels of different size, different numbers or types of abrasive flaps, different adhesive resins, etc. For general guidance, however, it may be stated that where an adhesive resin more thinly fluid than that employed in the specific example is employed, the initial rotational speed 45 utilized generally will be less than that shown. On the other hand where a viscous resin is employed the rotative speed will be greater since such viscous resin is less affected generally by centrifugal force of given magnitude than is a more thinly fluid resin. Similarly, where the 50 abrasive of the flap sections is of a fine grade, such that the interstices between the abrasive particles and between adjacent flap sections are relatively small, a greater rotational speed will be required to cause proper distribution 55 of adhesive resin than where the flap sections contain a coarse abrasive material. Also, a longer period of rotation at the greater rotative speed may be required in the case of a more viscous adhesive resin or in the case of a fine abrasive grit-size than where a more thinly fluid resin or a coarse abrasive grit-size is utilized. Time of rotation 60 at the final (i.e., slower) rotative speed largely will be governed by the curing time of the resin, a shorter time generally being required in the instance of a rapidly curing material than in the case of a slowly curing resin. These 65 principles are presented as a general indication of the direction to proceed in experimentally determining optimum conditions for a given specific case. It should be borne in mind, of course, that individual peculiarities of the specific materials employed may affect or tend to override the above principles and thus must be considered.

Commercially the procedures described herein have found most extensive use in the manufacture of wheel structures of small and medium diameter, up to about 11 inches in diameter, but inherently has characteristics which render it attractive for preparing larger wheels. It can 70 be used for making wide wheels as well as narrow wheels. 75

Various modifications of the procedures described herein undoubtedly suggest themselves, but it is to be understood that the specific example has been presented for the purpose of illustration, not for purposes of limitation, and that the scope of the invention is intended to be limited only by the disclosure as a whole, including the appended claims.

We claim:

1. In the method of forming an abrasive flap wheel wherein adjacent flap sections are rigidified and firmly rigidly adhesively bonded together over a substantial radially inner end area to form a rigid reinforced inner rim portion in said structure, the steps comprising forming a block of superimposed abrasive sheet flap sections, each flap section having at least one pair of opposed notches in the lateral edges adjacent one end thereof with said notches aligning to define opposed grooves in the lateral surfaces of said block, applying flexible stretchable binding means about said block with said binding means extending in and along each of said grooves thereby to unify the block, manipulating said unified block into an annulus with said one end of said flap sections forming the inner periphery thereof, inserting a circular forming member into a groove in each of said lateral surfaces to perfect the shape of said annulus, said sections each being provided with a coating of a liquid curable adhesive on each side thereof over a substantial area adjacent said ends, and curing said adhesive to a rigid hard firm state.

2. In the method of forming an abrasive flap wheel wherein adjacent flap sections are rigidified and firmly rigidly adhesively bonded together over a substantial radially inner end area to form a rigid reinforced inner rim portion in said structure, the steps comprising forming a block of superimposed abrasive sheet flap sections, each flap section having at least one pair of opposed notches in the lateral edges adjacent one end thereof with said notches aligning to define opposed grooves in the lateral surfaces of said block, applying flexible stretchable binding means about said block with said binding means extending in and along each of said grooves thereby to unify the block, manipulating said unified block into an annulus with said one end of said flap sections forming the inner periphery thereof, inserting a circular forming member into a groove in each of said lateral surfaces to perfect the shape of said annulus, incorporating liquid curable adhesive between each of said flap sections to provide essentially a complete coating of said adhesive on each side of said sections over a substantial area adjacent said ends, and curing said adhesive to a rigid hard firm state.

3. In the method of forming an abrasive flap wheel wherein adjacent flap sections are rigidified and firmly rigidly adhesively bonded together over a substantial radially inner end area to form a rigid reinforced inner rim portion in said structure, the steps comprising forming a block of superimposed abrasive sheet flap sections, each flap section having at least one pair of opposed notches in the lateral edges adjacent one end thereof with said notches aligning to define opposed grooves in the lateral surfaces of said block, applying flexible stretchable binding means about said block with said binding means extending in and along each of said grooves thereby to unify the block, manipulating said unified block into an annulus with said one end of said flap sections forming the inner periphery thereof by grasping the opposite end portions of said block and quickly bringing them around in a generally circular path toward one another until the flap sections on each end come into abutting juxtaposed relationship, incorporating liquid curable adhesive between each of said flap sections to provide essentially a complete coating of said adhesive on each side of said sections over a substantial area adjacent said ends, and curing said adhesive to a rigid hard firm state.

4. In the method of forming an abrasive flap wheel wherein adjacent flap sections are rigidified and firmly rigidly adhesively bonded together over a substantial radially inner end area to form a rigid reinforced inner rim portion in said structure, the steps comprising forming a block of superimposed abrasive sheet flap sections, each flap section having at least one pair of opposed notches in the lateral edges adjacent one end thereof with said notches aligning to define opposed grooves in the lateral surfaces of said block, applying a flexible stretchable rubber-like binder of continuous length about said block with said binder extending in and along each of said grooves thereby to unify the block, manipulating said unified block into an annulus with said one end of said flap sections forming the inner periphery thereof, inserting a circular forming member into a groove in each of said lateral surfaces to perfect the shape of said annulus, rotating said annulus and adding liquid curable adhesive to the inner peripheral portion thereof thereby utilizing centrifugal force to incorporate said adhesive between each of said flap sections to provide essentially a complete coating of said adhesive on each side of said sections over a substantial area adjacent said ends, and curing said adhesive to a rigid hard firm state.
5. In the method of forming an abrasive flap wheel wherein adjacent flap sections are rigidified and firmly rigidly adhesively bonded together over a substantial radially inner end area to form a rigid reinforced inner rim portion in said structure, the steps comprising forming a block of superimposed abrasive sheet flap sections, each flap section having at least one pair of opposed notches in the lateral edges adjacent one end thereof with said notches aligning to define opposed grooves in the lateral surfaces of said block, applying a flexible stretchable rubber-like binder of continuous length about said block with said binder extending in and along each of said grooves thereby to unify the block, manipulating said unified block into an annulus with said one end of said flap sections forming the inner periphery thereof by grasping the opposite end portions of said block and quickly bringing them around in a generally circular path toward one another until the flap sections on each end come into abutting juxtaposed relationship, incorporating liquid curable adhesive between each of said flap sections to provide essentially a complete coating of said adhesive on each side of said sections over a substantial area adjacent said ends, and curing said adhesive to a rigid hard firm state.
6. In the method of forming an abrasive flap wheel wherein adjacent flap sections are rigidified and firmly rigidly adhesively bonded together over a substantial radially inner end area to form a rigid reinforced inner rim portion in said structure, the steps comprising forming a block of superimposed abrasive sheet flap sections, each flap section having at least one pair of opposed notches in the lateral edges adjacent one end thereof with said notches aligning to define opposed grooves in the lateral surfaces of said block, applying flexible stretchable binding means about said block with said binding means extending in and along each of said grooves thereby to unify the block, and manipulating said unified block into an annulus with said one end of said flap sections forming the inner periphery thereof.
